UNITED STATES PATENT OFFICE.

JOHN H. BROWN, OF JERSEY CITY, NEW JERSEY.

GUN AND PROJECTILE THEREFOR.

No. 895,154.

Specification of Letters Patent.

Patented Aug. 4, 1908.

Application filed January 10, 1906. Serial No. 295,356.

To all whom it may concern:

Be it known that I, JOHN H. BROWN, a citizen of the United States, and resident of Jersey City, in the county of Hudson and State of New Jersey, have invented a new and useful Improvement in Guns and Projectiles Therefor, of which the following is a specification.

My invention relates to an improvement in guns and projectiles therefor and particularly to guns where the projectile is inserted into the barrel through the powder chamber, the object being to provide effective means for preventing the escape of gases past the gas check or a soft metal ring on the projectile during the passage of the projectile through the barrel in firing.

The recent experiments have emphasized the fact that the disastrous scoring or erosion on the interior of the bore of high power guns is due to the escape of the gases from the explosive charge past the heel of the projectile and more particularly to the escape of such gases during the initial movement of the projectile after the explosive charge is fired.

To overcome this escape of the gas, I provide means for the advance of the projectile to a limited extent before it is retarded by the engagement of its soft metal rings with the rifle grooves of the barrel and utilize this comparatively free advance movement to compress the gas check tightly around the projectile at or near the heel thereof so that when the projectile reaches a point where its soft metal rings engage the rifle grooves it will have an effective gas check surrounding it at or near its heel and, furthermore, it will strike the rifle grooves under more or less momentum and hence there will be less retarding effect during its early movement and hence less tendency for the gas to escape past the gas check.

In the accompanying drawings, Figure 1 is in view in section through the barrel of a gun in proximity to the powder chamber showing the projectile therein in side elevation, Fig. 2 is a partial section through the gun and through the soft metal ring, gas check and locking ring at the heel of the projectile, and Fig. 3 is a view similar to Fig. 1 showing a modified structure.

Referring to Figs. 1 and 2, the barrel of the gun is denoted by 1, its powder chamber by 2 and the rifle bore by 3. The body of the projectile is denoted by 4 and it is provided

at its heel end with a soft metal or other suitable ring 5 for entering the grooves in the rifle portion of the barrel to impart a rotary motion to the projectile. The projectile is further provided preferably in juxtaposition to the ring 5 with a gas check 6 of some suitable compressible material in the form of an annular ring for example of what is known in the art as vegetable fiber, and to the rear of this a locking ring 7 is screwed onto the heel of the projectile to hold the ring 5 and gas check 6 in position. The rifle portion 3 of the barrel terminates, as clearly shown in Fig. 2, a greater or lesser distance in advance of the front edge of the ring 5 and from that point to the powder chamber 2, the interior of the barrel has a smooth bore, the said smooth bore section being indicated by 8. The gas check 6 is normally of greater diameter than the smooth bore portion 8 of the barrel so that when the projectile is forced into position, as, for example, by hand, and pushed toward the muzzle with all the manual pressure that can well be given it, it will tend to compress the advance edge of the gas check 6 and this will, by its frictional contact with the interior of the bore, arrest the projectile with the front edge of the ring a greater or lesser distance back from the beginning of the rifle portion 3 of the barrel.

If preferred, the gas check may be constructed with its forward edge somewhat thinner than the rear edge, giving it a slight taper and so assisting it to enter the smooth bore portion of the barrel under manual pressure.

When the explosive charge within the chamber 2 is fired, the first effect will be to force the projectile forward until the ring 5 engages the rifle portion of the barrel and this advance movement of the projectile will be comparatively easy because there will be no retarding effect due to the forcing of the metal ring 5 into the grooves of the barrel and this free forward movement of the projectile will, at the same time, compress the gas check 6 so as to effectually shut out the escape of gases past it when the ring 5 finally does engage the grooves in the barrel. Furthermore, the projectile having advanced freely for a short distance, will cause the ring 5 to strike the rifle grooves under momentum and hence the retarding effect will be less abrupt and the continued pressure of the explosive charge thoroughly checked by the

compressed gas check ring will force the projectile forward without escaping past it and hence without damaging the interior of the barrel by scoring or erosion.

5 Where the ring 5 is located in its preferred form, as shown in Fig. 2, the forward portion of the projectile at the base of the conical forward end, for example, at 9, is made somewhat larger than the body so as to prevent 10 the forward end of the projectile from wobbling during its passage through the barrel.

In the form shown in Fig. 3, the ring 5 for engaging the rifle grooves is located at the forward portion of the projectile near the 15 base of the tapered forward end and the rifle grooves are stopped at the point 10 a short distance in advance of the forward edge of the ring 5 so as to permit the free initial movement of the projectile to compress the 20 gas check ring 6 at the heel of the projectile. The modification shown in Fig. 3, therefore consists simply in spacing the ring 5 from the 25 gas check 6 and increasing the length of the smooth bore portion of the barrel adjacent to the powder chamber.

What I claim is:—

The combination with a gun barrel provided with a powder chamber, a rifle portion and a smooth bore portion intermediate of the rifle portion and the powder chamber, 30 of a projectile provided with a metal ring for engaging the rifle grooves, the said ring being located within the smooth bore portion of the barrel and spaced from the rifle portion of the barrel when the projectile is in position for 35 firing, the said projectile being further provided with a gas check of compressible material of greater normal diameter than the diameter of the smooth bore portion of the barrel and so located at the heel of the projectile 40 as to be compressed by the initial movement of the projectile.

In testimony, that I claim the foregoing as my invention, I have signed my name in presence of two witnesses, this ninth day of 45 January 1906.

JOHN H. BROWN.
